UNITED STATES PATENT OFFICE.

CHARLES M. MCFARLAND, OF WORCESTER, MASSACHUSETTS.

DESIGN FOR A SPOON, &c.

SPECIFICATION forming part of Design No. 21,165, dated November 10, 1891.

Application filed May 4, 1891. Serial No. 391,586. Term of patent 3½ years.

To all whom it may concern:

Be it known that I, CHARLES M. MCFARLAND, a citizen of the United States, residing at Worcester, in the county of Worcester and State of Massachusetts, have invented and produced a new and Original Design for Handles of Spoons, Forks, &c., of which the following is a specification, reference being had to the accompanying drawing, forming a part thereof.

My design is for the handle of a spoon, fork, &c., and the leading feature of my design consists in the original shape and ornamentation of the handle.

15 The drawing represents a front view of a spoon embodying my design.

In the accompanying drawing, 1 is a spoon with my design for the handle thereof. Said design is restricted to the handle of the spoon, 20 the bowl of the spoon being left plain.

On the front of the handle of the spoon, at the upper end thereof, is a man's head or bust

2 to represent the likeness or conventional representation of Christopher Columbus. Below the head or bust is a scroll, and within 25 the scroll is the representation of a ship. Below the scroll is the representation of an island.

The edge of the spoon-handle is smooth and of uniform contour, and the handle is made of 30 uniform taper from the upper end thereof to the bowl of the spoon.

What I claim is—

The design for handles of spoons, forks, &c., comprising a smooth edge of uniform taper from the upper end thereof to the bowl, 35 a representation of the head of Christopher Columbus on the front of the handle, and a scroll, a ship, and an island under said head, substantially as set forth.

CHARLES M. MCFARLAND.
